COIN CHUTE

Bernhard C. Grunig, Chicago, Ill., assignor to
 A. B. T. Manufacturing Corp., Chicago, Ill., a
 corporation of Illinois

Application October 14, 1938, Serial No. 235,013

2 Claims. (Cl. 194—97)

This invention relates to improvements in check-controlled apparatus and has as its principal object the provision of means for preventing fraudulent or accidental jamming of coins in a coin testing apparatus of the type including a reciprocable coin slide and a coin feeding chute coating therewith for feeding coins away from the testing apparatus after acceptance, the invention relating especially to the provision of means on said slide which will be normally in blocking position relative to the feeding chute and which will be effective to prevent the retrograde or return movement of previously fed coins into the coin testing device.

Viewed from another aspect, it is an object of the invention to provide a coin testing device having some form of reciprocable mechanism for effecting transport of a coin from a depositing position to a discharge position, and a laterally projecting feeding chute for accepted coins and mounted to receive accepted coins at said discharge position and move the coins in step by step progression along the chute for deposit in a receptacle, said slide mechanism, including a slide member having an offset edge portion, constituting a blocking member which is normally disposed in blocking position across the mouth of the feeding chute, whereby deliberate or accidental movement of the coins back into the coin testing device will be effectively prevented.

Other objects, advantages, and economies residing in the invention relate to the form, location, and operation of certain structural features thereof, all of which will become apparent as the following description proceeds in view of the annexed drawing, in which:

Fig. 1 is a top plan view of a combination check testing unit and feeding chute;

Fig. 2 is a fragmentary vertical longitudinal section along line 2—2 of Fig. 1;

Fig. 3 is a fragmentary lateral section, viewed along line 3—3 of Fig. 1;

Fig. 4 is a fragmentary perspective of the feeding mechanism for the feed chute;

Fig. 5 is another fragmentary perspective similar to Fig. 4, but showing the feeding mechanism in feeding position; and

Fig. 6 is a perspective view of the coin transporting slide provided with the novel blocking means.

This application includes matter divided from U. S. application Serial No. 146,836, as well as matter not disclosed in said application.

In a preferred embodiment of the invention,

there is provided a coin testing device including a sleeve-like frame member 10 having a lateral mounting plate 11 adapted for attachment to the wall of a cabinet so as to dispose the front or handle portion 12 of a reciprocable coin slide 13, mounted in the sleeve portion of the frame, for access exteriorly of the cabinet.

The slide 13 is provided with a coin receiving pocket 14 in which a suitable coin is placed for transport by subsequent movement of the slide 10 inwardly of the cabinet (to the right, Fig. 1) so as to move the coin past certain testing means including, for example, the dogs 15 and 16 and the magnet 17, the testing means being of any suitable form, such as for example as that described in detail in the aforesaid copending application.

Referring to Fig. 2, the frame structure for the testing apparatus is arranged to provide a shelf or ledge 18 at a level below that of the slide 13 and rearwardly of the testing means, so that the transported coin, after passing the testing means, may drop onto the ledge 18 for subsequent movement by a depending lug 19 (Fig. 1) in the slide 13, into a well 20 lying beneath a sight opening 21 above the slide.

A spring presser finger 22 serves to guide the coin downwardly toward a coin pocket 23 in an auxiliary coin slide 24 (the form of which is shown in Fig. 6) for subsequent deposit on the floor 25 of an auxiliary coin feeding chute 26 (Fig. 5).

The coin feeding chute 26 is preferably of the type described in the aforesaid copending application and is constructed so that the floor section 25 thereof extends parallel with the frame structure 10 beneath the auxiliary slide 24, being attached to the bottom of the frame by means such as the screws 27, there being a laterally projecting chute section 28 (Figs. 1 and 5) having a mouth 29 positioned substantially opposite the bottom of the well 20 so that accepted coin elements passing through the pocket 23 in the auxiliary slide 24 onto the floor 25 may be moved laterally into the feeding chute.

The foregoing lateral movement of accepted coins is preferably accomplished by a feeding cam 30 pivotally mounted as at 31 on the under side of the auxiliary slide 24 for oscillatory movement toward and away from the mouth 29 of the feeding chute, the cam being so designed that when it is in the position illustrated in Fig. 4, the nose portion 32 thereof will be at the far side of a coin element indicated in dotted lines at 33. The feeding cam 30 is provided with an irregular cam slot 34 shaped and situated to

receive a stationary camming pin 35 mounted on the floor 25 in such manner that as the auxiliary slide 24 is reciprocated, the cam member 30 will be oscillated as a result of the movement of the slot portion 34 relative to the pin 35, so that coin elements 33 will be swept into the mouth 29 of the feeding chute.

The auxiliary slide is reciprocated through the agency of an upstanding pin 36 mounted thereon so as to project into a longitudinal slot 37 (Figs. 1 and 3) in the main slide 13, there being a shoulder 38 on slide 13 and projecting into the slot 37 so that after the main slide 13 has been moved inwardly (toward the right, Fig. 1) a certain amount less than its entire displacement, the shoulder 38 will bear against the pin 36 and move the auxiliary slide the remainder of the distance with the main slide, and since the feeding cam 30 is pivoted as at 31 to the auxiliary slide, the cam will be moved in a direction to push a coin 33 into the feeding chute.

It is possible to cause deliberate or accidental jamming of the entire apparatus by rattling, jarring, or striking the apparatus, and particularly the auxiliary feed chute 28, in a manner which will effect a rearward or retrograde movement of coins in the feed chute back through the mouth 29 and into the bottom region of the well 20, the feeding cam 30 normally being withdrawn as in Fig. 4 when the slide 13 is in a normal coin receiving position of Fig. 1.

In order to prevent such accidental or deliberate jamming of the mechanism, the invention provides means for automatically blocking the mouth of the auxiliary feeding chute at all times except when coin elements are actually being moved into the mouth of the feeding chute. A preferred arrangement of this blocking means is shown particularly in Fig. 6 wherein the auxiliary coin slide 24 has an offset or depending longitudinal flange 40 arranged on the longitudinal edge portion thereof nearest the feeding chute section 28, the flange 40 being so arranged and constructed (Figs. 3 and 5) that when the main slide 13 is in its normal coin receiving position, and the auxiliary slide 24 is also in normal position with its pocket 23 in register with the well 20, the flange portion 40 will be disposed in coin blocking position across the mouth 29 leading to the feeding chute 28, so that retrograde movement of coin elements from the latter is positively prevented regardless of the cause.

The feeding chute 23 may be of any desired construction and may include additional testing means, such for example as the undersized-diameter drop-out opening 45 indicated in dotted lines in Fig. 1, and the cooperating spring presser 46

which is effective to support coin elements of proper diameter in their step by step movement past the opening 45 and toward the discharge end 47 of the feeding chute. A detailed description of a suitable feeding chute of this type is set forth in the aforementioned copending application.

In its broader aspects, the invention relates particularly to the provision of the automatic blocking means actuated by the auxiliary slide 24 for blocking movement of coin elements into a feeding chute, whether that chute includes additional testing mechanism or not; and it may be pointed out that the blocking means may be applied to the main slide 13 as well as to any auxiliary slide mechanism. All equivalent changes in form, location, and operation of the means of the invention are intentionally included within the call of the appended claims.

Having thus described my invention, what I claim as new and desire to protect by Letters Patent is:

1. In a device of the class described including a reciprocable coin slide arranged to discharge coins into the mouth of a coin chute and means in said mouth and actuated by said slide, upon each movement of the latter from a certain normal position, for moving coins in succession into the chute, the combination with said slide of means carried thereby into position to block movement of coins between said mouth and said chute when said slide is in the aforesaid normal position, said last-mentioned blocking means being moved out of blocking position when said slide is moved a predetermined amount out of normal position as aforesaid to actuate said means for moving a coin from the mouth into the chute.

2. In a device of the class described including a main reciprocable coin transporting slide and an auxiliary coin moving slide coacting with the first slide to discharge coins into the mouth of an auxiliary coin chute, together with means actuated by said auxiliary slide, responsive to movement of the latter out of a certain normal inoperative position, for moving coins from said mouth into the auxiliary chute, the combination of blocking means comprising a flange on said auxiliary slide and disposed by the latter in a position to block passage of coins between said mouth and said chute when said auxiliary slide is in said certain normal position, said flange being moved by the auxiliary slide out of blocking position while said coin moving means is being actuated by the slide to move a coin from the mouth into the chute as aforesaid.

BERNHARD C. GRUNIG.
